UNITED STATES PATENT OFFICE.

GEORGE WALKER, OF SAN FRANCISCO, CALIFORNIA.

GAS-HEATER.

1,282,998.

Specification of Letters Patent.

Patented Oct. 29, 1918.

Application filed April 26, 1918. Serial No. 230,971.

To all whom it may concern:

Be it known that I, GEORGE WALKER, a citizen of the United States, residing at San Francisco, in the county of San Francisco

5 and State of California, have invented certain new and useful Improvements in Gas-Heaters, of which the following is a specification.

This invention relates to a stove for heating purposes and while designed mainly for use with illuminating gas is not limited in its use to such fuel, as any form of gas or oil burner might be provided for it.

The invention consists especially in the 15 construction of the upper portion of the stove whereby the heated air currents are forced to travel through this portion of the stove before escaping to an outlet pipe, in combination with products of combustion, in 20 such manner that they will give up a maximum amount of their heat units, thus causing the stove to radiate a great quantity of heat compared with the amount of fuel consumed.

25 The invention further consists in the novel features of construction hereinafter described, pointed out in the claims and shown in the accompanying drawings, in which:

Figure 1 is a vertical section.

30 Fig. 2 is a section on the line 2—2 of Fig. 1.

Fig. 3 is a section on the line 3—3 of Fig. 1.

In the drawings 1 designates a suitable 35 elevated base having a central opening surrounded by a depending flange 2. Within this flange is placed an air inlet pipe 3. Concentric with said pipe, and below the top of it, is a burner 4, supplied by a pipe 5.

40 A stove section 6 is mounted on the base and is provided with paneled doors 7 through which the burner flame can be examined and through which the burner can be ignited.

45 An upper section 8 is secured by a slip joint 9 to the section 6, these sections constituting the stove body or casing.

It is the chambers arranged within and 50 the parts carried by the upper section of the casing that constitute the main feature of my invention. The section 8 is subdivided into upper and lower compartments by a casting 11 riveted or otherwise secured in place. The casting is centrally cut out and 55 on its upper face is formed a U-shaped rib

the bow portion of which encircles one-half of this central opening, said rib being designated at 13, and shown most clearly in Fig. 2.

More or less parallel with the rib 13 is an 60 under rib 14, the rib 14 lying approximately midway between the rib 13 and upper and lower ribs 15 and 16, the latter ribs being in the form of open rings, the rib 15 joining the outer ends of the rib 13, as shown in 65 Fig. 2.

Fitting in the central opening of the casting and bolted to the rib 13 is a depending tubular air conduit 17, the upper portion of which is partly cut out as at 18 to give 70 lateral communication with the upper portion or compartment of the section 8. This upper portion is divided into two compartments by a sheet metal wall 19 secured to the rib 13 which wall is continued by the 75 upper end portion of the conduit 17. The inclosed portion forms a dead air space while between the casing 8 and the wall 19 is formed a circular air passage the course of which is shown in Fig. 2. 80

Communication between the passage mentioned and the lower compartment of section 8 is provided for by an opening 20 in the casting 11. To the under rib 14 is secured a sheet metal wall 21 having an opening 22. Concentric with this latter wall is a semi-circular wall 23 secured to the rib 16 so that the lower portion of the section 8 is subdivided into three circular passages 90 communicating with each other, the innermost one opening outwardly and laterally into an escape pipe 29.

In the section 6 is suspended a cylinder 26, open at the top and closed at the bottom by an inverted cone 27. The conduit 17 95 dips into this cone and is secured thereto by angled brackets 28, so that the cylinder and cone are supported from rib 13 of the casting 11.

A plate 24 forms the bottom of the section 8.

A cover or top piece 10 fits over the section 8 being locked in the usual manner to a cover plate 10a.

In operation air is fed to the burner 105 through the pipe 3 and the heated air and products of combustion rise through the conduit 17, thence around the circular passage in the upper compartment of section 8, down through the opening 20 and thence 110

successively through the passages in the lower compartment and out through the pipe 29.

The advantages of this construction are 5 that the heated vapors are forced directly to the top and around the outer wall of the stove while at their greatest temperature, passing to the center of the lower compartment as they give up heat units to the top 10 and outer wall of the stove, and finally to the pipe 29 when they have been robbed of the largest possible amount of heat units practical in a device of this kind, the direction of the air currents being indicated by 15 arrows.

It will be noted that the cone 27 dips slightly into the air inlet pipe 3, this cone therefore acts as a baffle plate or deflector as it not only throws the hot air over the burner 20 but prevents the upper draft through the conduit 17 drawing any of the fresh cool air into the upper portion of the stove. After passing over the burner the air is forced by the cylinder 26 to travel up along the sides 25 of the section 6 until it passes into the top of the cylinder, thereby heating the side walls of the stove to a greater extent than if it had not been forced against them.

As the air is forced downwardly into the 30 cone it again approaches the burner and regains more or less in temperature making up for the amount lost through the wall of section 6. The air thus practically reheated in the cone rises through the conduit and is 35 again brought into direct contact with the outer wall of the upper section as previously explained.

A gasolene burner with drip pan may be substituted for the form of burner shown.

40 What I claim is:

1. In a device of the kind described, a stove formed in upper and lower sections detachably connected, the upper section being formed of upper and lower communicating 45 compartments, the lower of which opens to a suitable exhaust, a burner arranged in the lower stove section, a depending air conduit carried by the upper section and projecting into the lower section, a cylinder surrounding the lower portion of the conduit and having a conical bottom supported by and spaced from the conduit, and forming a deflector, the conduit communicating with the

upper compartment of the upper stove section, and means for centrally admitting air 55 to the lower section.

2. In a stove or heater having upper and lower sections, the upper section being divided by a casting into upper and lower compartments and having top and bottom plates, 60 ribs formed on the upper and under faces of said casting, the casting having a central opening, a hot air conduit carried by one of said ribs and extending downwardly through the lower compartment, opening laterally 65 into the upper compartment, vertically arranged walls secured to the ribs in the upper and lower compartments, respectively, forming air passages, the casting having a vent opening affording communication between 70 the upper and lower compartments adjacent the outer side wall of the stove, and an exhaust pipe having communication with the innermost passage of the lower compartment, as and for the purpose set forth. 75

3. The combination in a stove with a base having a source of heat and a central air inlet, of an upper section subdivided into upper and lower compartments, the upper compartment having a central dead air chamber 80 encircled by a hot air passage, and the lower compartment having a series of concentric air passages communicating with each other, the outermost of said passages 85 communicating with the air passage of the upper compartment, and the innermost passage being in communication with a suitable exhaust, a depending hot air conduit carried by the upper section and passing through the lower compartment and having communication 90 with the air passage of the upper compartment, and an inverted cone carried by and spaced from the lower end of the said conduit, the hot air traveling downwardly into the cone, thence upwardly through the 95 conduit, around the first mentioned air passage, thence into the lower compartment and successively through the passages of said compartment and finally from the central portion thereof to the outer air, as and for 100 the purpose set forth.

In testimony whereof I affix my signature.
GEORGE WALKER.
